INVENTOR:

UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed June 3, 1926. Serial No. 113,380.

My invention relates to railway traffic controlling apparatus, and particularly to apparatus of the type comprising train carried governing mechanism controlled by energy received from the trackway.

I will describe one form of railway traffic controlling apparatus embodying my invention and will then point out the novel features thereof in claims.

10 In the accompanying drawings, Fig. 1 is a view, partly diagrammatic, showing one form of train carried governing mechanism embodying my invention. Fig. 2 is a diagrammatic view illustrating one form of trackway apparatus suitable for co-operation with train carried mechanism shown in Fig. 1 and also embodying my invention.

Similar reference characters refer to similar parts in both views.

20 Referring first to Fig. 2, the reference characters 1 and 1^a designate the track rails of a stretch of railway track over which traffic normally moves in the direction indicated by the arrow. These track rails are 25 divided, by means of insulated joints 2, into a plurality of successive track sections A—B, B—C, etc. Each track section is provided with a track relay designated by the reference character R with an exponent corre-

30 sponding to the location and connected across the rails adjacent the entrance end of the section. Each such track relay is responsive to track circuit current supplied to the corresponding section from a suitable source 35 such as a track battery designated by the reference character D with an appropriate distinguishing exponent and connected across the rails adjacent the exit end of the section.

40 Each track section is further provided with a trackway signal designated by the reference character S with a distinguishing exponent. In the form here shown each signal S is of the three-position semaphore type and is located adjacent the entrance end of the associated section, but this particular form and location of signals is not essential. The circuits for controlling the signals S form no part of my present invention and are omitted from the drawing for the sake of simplicity. For present purposes it is sufficient to state that each signal is so controlled that when the corresponding section is occupied the signal indicates stop;

when the corresponding section is unoccupied and the section next in advance is occupied, the signal indicates caution; and when the corresponding section and the section next in advance are both unoccupied, the signal indicates proceed.

55 Means are also provided for supplying each track section with alternating train controlling current which flows through the two rails of the section in series. As here shown the immediate supply of such train controlling current for each section is a transformer, designated by the reference character T with an appropriate exponent, and having a secondary 5 connected across the rails of the associated section in series with 60 the track battery D for the same section. The primary 6 of each transformer T is supplied with alternating current over a front contact 9—9^a of the adjacent track relay R 65 from line wires 3 and 3^a. The line wires 3 and 3^a are constantly supplied with alternating current from a suitable source such as an alternator M. It will therefore be plain that each section is supplied with alternating train controlling current when the 70 track relay for the section next in advance is energized.

75 Each track section is also provided with an auxiliary transformer designated by the reference character K with an exponent corresponding to the location and having a secondary winding 7 connected across the rails a short distance in advance of the entrance end of the associated section. A resistor 77 is interposed between the secondary 7 of 80 each such transformer and the rails so that the secondary will not shunt the adjacent track relay R. The primary 8 of each transformer K is supplied with alternating current from line wires 3 and 3^a over back contact 9—9^b of the adjacent track relay R. It follows that each section is supplied with train controlling current between the entrance end of the section and the associated transformer K when the corresponding 85 track relay is de-energized.

90 As shown in the drawing the section to the right of point C is occupied by a train indicated diagrammatically at V. Signal S^c therefore indicates stop, signal S^b indicates caution, and signal S^a indicates proceed. Track relay R^c is de-energized and transformer K^c is therefore energized. The 95

supply of train controlling current to section B—C is interrupted because front contact 9—9^a of relay R^c is open, but this section is being supplied with track circuit current from battery D^c so that relay R^b is energized. Section A—B is therefore supplied with track circuit current and also with train controlling current and relay R^a is energized. In a similar manner the section to the left of point A is supplied with train controlling current and also with track circuit current.

The section to the left of point A is occupied by a following train designated by the reference character V^a, and which is provided with train carried governing mechanism embodying my invention. Referring now also to Fig. 1, carried on the locomotive of train V^a in advance of the forward axle 4 are two magnetizable cores 10 and 10^a located in inductive relation with the two track rails 1 and 1^a respectively. Core 10 is provided with a winding 11 and core 10^a is provided with a similar winding 11^a, the two windings 11 and 11^a being connected in series in such manner that the voltages induced therein by alternating currents flowing in opposite directions in the two track rails at any instant are additive. The windings 11 and 11^a are connected, preferably through an amplifier 12, with a main relay D.

The relay D controls two signals here shown as electric lamps 48 and 49, and also controls a magnet valve F. The reference character 19 designates a pipe normally supplied with fluid pressure, usually air, and arranged to cause an automatic application of the brakes when the pressure in the pipe is reduced. Pressure in pipe 19 is controlled by an application valve G which is in turn controlled by the magnet valve F, and by a pilot valve P which is in turn controlled by a manually operable acknowledging valve H.

Valve F comprises a valve body 59 containing a valve stem 60, provided with an armature 15 and a winding 16. When winding 16 is energized stem 60 is moved downwardly against the bias of a spring 61 so that pipe 70 is supplied with fluid pressure from a suitable source not shown in the drawing, through pipe O². When winding 16 is de-energized, stem 60 is forced up by spring 61, so that pipe O² is blanked and pipe 70 is connected with atmosphere through a restricted orifice 62.

The application valve G comprises a valve body 13 provided with a chamber 57 containing a piston 56. Operated by the piston 56 is a valve stem 14. Chamber 57 is constantly connected with a timing reservoir 58 and pipe 70, and when this chamber is supplied with fluid pressure, piston 56 moves downwardly, carrying the stem 14 against the bias of a spring 17 to a position

in which pipe 19 is blanked and a pipe 20 is connected with atmosphere through a port 18. When the pressure in chamber 57 is sufficiently reduced, spring 17 moves stem 14 upwardly to a position in which pipe 19 is connected with pipe 20 and port 18 is blanked. Under normal conditions pipe 20 is connected, through valve P, with pipe 29 and a stop reservoir 30.

When relay D is energized, current is supplied to winding 16 of valve F from a suitable source of energy such as a battery 41, over wire 42, front contact 40 of relay D, wire 43, winding 16 of valve F, and wire 44 back to battery 41. Fluid pressure therefore is supplied from pipe O², through valve F, to timing reservoir 58 and chamber 57 of valve G. Stem 14 of valve G therefore occupies its lower position so that pipe 19 is blanked and reservoir 30 is connected with atmosphere through port 18 of valve G. When relay D becomes de-energized, however, valve F reverses, and pressure in reservoir 58 and chamber 57 is slowly dissipated to atmosphere through port 62 in valve F. After a time interval the pressure in chamber 57 is reduced to a value low enough to permit spring 17 to raise stem 14, whereupon valve G reverses. Stop reservoir 30 is then disconnected from atmosphere and is connected with pipe 19, thereby reducing the pressure in pipe 19 and causing an automatic application of the brakes. When relay D is energized current also flows from battery 41 through wires 42 and 45, front contact 46 of relay D, wire 47, lamp 48, wire 50, contact 51 and wires 52 and 53, back to battery 41. Lamp 48 is then lighted to indicate proceed. When relay D is de-energized, however, the circuit just traced for lamp 48 is open and another circuit is closed from battery 41, through wires 42 and 45, back contact 46 of relay D, wire 54, lamp 49, and wires 55 and 53 back to battery 41. Lamp 49 is then lighted to indicate caution.

The acknowledging valve H comprises a valve body 39 containing a valve 37 controlled by a manually operable handle 38. An acknowledging reservoir 36 is normally connected, through pipe 35 and valve H, with a pipe O which is constantly connected with a suitable source of air pressure not shown in the drawing. When handle 38 of valve H is moved to the left, reservoir 36 is disconnected from pipe O and is connected through pipe 35 and valve H with pipe 24.

The pilot valve P comprises a valve body 21 containing a chamber 22 having a reciprocable piston 25 therein. Piston 25 operates a stem 26 carrying a piston valve 28, and a poppet valve 28^a, these parts being biased to their lower positions by a spring 27. Pipe 24 communicating with valve H is connected with chamber 22 beneath piston 25. When piston 25 occupies its lower po-

sition valve 28 connects pipe 20 with pipe 29, and valve 28^a is closed; but when the acknowledging valve H is operated the pressure normally existing in acknowledging reservoir 36 is discharged into cylinder 22, driving piston 25 upwardly. Stem 26 therefore moves upwardly and pipe 29 is then supplied with fluid pressure from a source not shown in the drawing through pipe O¹ and valve 28^a, so that stop reservoir 30 becomes charged. Valve 28 also moves upwardly to blank pipe 20. If under these conditions, valve G should reverse to connect pipe 19 with pipe 20 there would be substantially no decrease in the pressure in pipe 19 and hence the brakes would not be applied.

It will be noticed that a restricted orifice 23 connects chamber 22 with atmosphere. After the expiration of a time interval the pressure supplied to chamber 22 from reservoir 36 is decreased by dissipation to atmosphere through orifice 23 so that spring 27 returns piston 25 to its lower position, thereby closing valve 28^a and opening pipe 20 to pipe 29. This operation does not cause a brake application, however, even if valve G be reversed, because reservoir 30 has already been charged by pressure from pipe O¹ and therefore the connection of pipe 19 to this charged reservoir does not decrease the pressure in pipe 19.

A pneumatic relay designated by the reference character J comprises a body 32 containing a piston 33 which is biased to its lower position by a spring 34. The underside of piston 33 is connected, by means of pipe 31 with pipe 29. When reservoir 30 and pipe 29 are connected with atmosphere, piston 33 occupies its lower position under the influence of spring 34, and contact 51 which is operatively connected with piston 33 is then closed. When reservoir 30 is charged with fluid pressure, however, piston 33 is moved upwardly against the bias exerted by spring 34 to open contact 51. It will therefore be plain that lamp 48 cannot be lighted to indicate proceed unless the pressure in stop reservoir 30 is atmospheric, that is, unless the pneumatic apparatus is in proper condition to cause an automatic application of the brakes should relay D become de-energized.

Referring now also to Fig. 1, as the train V^a proceeds through the stretch of track shown in the drawing while it occupies section A—B, relay D is energized due to current from transformer T^B. With relay D energized, winding 16 of valve F is energized, and stem 14 of valve 6 occupies its lower position. I will assume that valve H occupies the position in which it is illustrated in Fig. 1, so that piston 25 of valve P occupies its lower position. Stop reservoir 30 is therefore connected with atmosphere through port 18 of valve G, and pipe 19 is blanked at valve G. Piston 33 of relay J occupies its lower position, so contact 51 of this relay is closed, and lamp 48 is lighted. As the train enters section B—C relay R^B becomes de-energized, closing the circuit for primary 8 of transformer K^B. Relay D is therefore energized due to current from transformer K^B until the train passes the point of connection thereof with the rails. When this happens, relay D becomes de-energized. Lamp 48 is therefore extinguished and lamp 49 is lighted to call the attention of the engineman to the change in traffic conditions. The opening of front contact 40 of relay D also de-energizes winding 16 of valve F. Stem 60 of this valve therefore moves to its upper position, venting reservoir 58 and chamber 57 of valve G to atmosphere through port 62 of valve F. After a short time interval stem 14 of valve G rises, connecting pipe 19 with pipe 20. If valve H is not operated this operation of valve G causes an automatic application of the brakes by connecting pipe 19 with the stop reservoir 30. After lamp 48 is extinguished the engineman has a time interval, prior to the operation of valve G during which he may prevent the automatic brake application by operating valve H. Should he do this before valve G operates, piston 25 of valve P is moved upwardly to blank pipe 20, and reservoir 30 is charged with fluid pressure from pipe O¹. Piston 33 of relay J is then moved upwardly to open contact 51. After the pressure in reservoir 36 has been exhausted through port 23 of valve P, piston 25 will return to its lower position, but without causing an automatic application of the brakes, because stop reservoir 30 has been charged to the same pressure as pipe 19. As the train proceeds through section B—C, therefore, relay D is de-energized and lamp 49 is lighted to indicate caution, but no automatic brake application is incurred if the engineman has acknowledged.

As the train enters the section to the right of point C, current from transformer K^C energizes relay D. The circuit for lamp 49 is now opened at back contact 46 of relay D and the circuit for winding 16 of valve F is closed at front contact 40; valve F, therefore reverses and pressure is supplied to chamber 57 of valve G, moving stem 14 of that valve to its lower position to blank pipe 19, and vent reservoir 30 to atmosphere through port 18. Piston 33 of valve J then returns to its lower position closing contact 51. Lamp 48 therefore becomes lighted. When the train passes transformer K^C relay D again becomes de-energized to cause an automatic brake application by connecting the pipe 19 with the reservoir 30. If, however, the engineman operates valve H to acknowledge the change in traffic conditions shown by the lighting of lamp 49 prior to the opera-

tion of valve G, valve P will be operated to again prevent an automatic brake application, as explained hereinbefore. If the engineman sees and acknowledges the stop indication displayed by signal S^c before relay D becomes energized at C, valve P will remain reversed as the train passes the portion of track between C and K^c, and will maintain reservoir 30 charged and prevent an automatic application of the brakes upon de-energization of relay D in passing transformer K^c and will maintain contact 51 open to prevent lighting of lamp 48 even though relay D is energized. It will therefore be seen that if the engineman passes the stop signal S^c without acknowledging, the brakes will be automatically applied shortly after the train passes transformer K^c. If, however, the engineman does acknowledge the stop signal S^c, both lamps 48 and 49 are extinguished until the train passes transformer K^c. When the train passes the point of connection of transformer K^c, relay D again becomes de-energized so that lamp 49 is lighted to give a continuous caution indication through the section to the right of point C, or until relay D is again energized as by a change in traffic conditions.

Of course if train V is between point C and the point of connection of transformer K^c with the track rails when train V^a passes point C, relay D will not become energized, and the same thing is true if train V is beyond the transformer K^c but close enough thereto to materially reduce the difference of potential across the rails due to this transformer.

Should the valve G be reversed when relay D is energized, as by some defect in contact 40 or valve F, the reservoir 30 would be connected of course, with pipe 19, so that the reservoir would be charged with fluid pressure. Relay J would then be supplied with fluid pressure and contact 51 would be open so that lamp 48 would be extinguished even though contact 46 of relay D were closed. It follows that even though relay D is energized, lamp 48 cannot be lighted unless reservoir 30 is connected with atmosphere, that is, unless the apparatus is in proper condition to cause an automatic application should relay D become de-energized.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a pipe on a train normally supplied with fluid pressure and arranged to

apply the brakes when such pressure is reduced, a reservoir normally connected with atmosphere, means responsive to traffic conditions for at times connecting said pipe with said reservoir, manually operable means for at times supplying fluid pressure to said reservoir, a contact responsive to the pressure in said reservoir, and a signal controlled by said contact.

2. Railway traffic controlling apparatus comprising a pipe on a train normally supplied with fluid pressure and arranged to apply the brakes when such pressure is reduced, a reservoir normally connected with atmosphere, a relay on the train controlled in accordance with traffic conditions, a valve controlled by said relay and arranged normally to close said pipe but to at times connect the pipe with said reservoir, manually operable means for supplying said reservoir with fluid pressure, and a signal controlled by said relay and responsive to the pressure in said reservoir.

3. Railway traffic controlling apparatus comprising a pipe on a train normally supplied with fluid pressure and arranged to apply the brakes when such pressure is reduced, a reservoir normally connected with atmosphere, a relay on the train arranged to be energized under safe traffic conditions but to be de-energized when traffic conditions are dangerous, a valve controlled by said relay and arranged to close said pipe when the relay is energized but to connect said pipe with said reservoir when the relay is de-energized, manually operable means for supplying fluid pressure to said reservoir and effective for an interval of time to prevent connection of said reservoir with said pipe, a contact responsive to the pressure in said reservoir and arranged to be open when said reservoir is charged with fluid pressure, a signal, and a circuit for said signal including said contact and a front contact on said relay.

4. Railway traffic controlling apparatus comprising a pipe on a train normally supplied with fluid pressure and arranged to apply the brakes when such pressure is reduced, a reservoir normally connected with atmosphere, a relay on the train controlled in accordance with traffic conditions, a valve controlled by said relay and arranged to blank said pipe when the relay is energized but to connect the pipe with said reservoir at the expiration of a time interval following de-energization of the relay, manually operable means for supplying said reservoir with fluid pressure and a signal controlled by said relay and responsive to the pressure in said reservoir.

5. In combination, a stretch of railway track, a relay located on a train, means located partly in the trackway for normally energizing said relay but effective under un-

safe traffic conditions to successively de-energize, re-energize and de-energize said relay as the train proceeds through said stretch, a train carried reservoir normally connected with atmosphere, manually operable means for at times supplying fluid pressure to said reservoir, brake applying apparatus on the train controlled by said relay and responsive at times to the pressure in said reservoir, a contact responsive to the pressure in said reservoir, and a signal controlled by said contact.

6. In combination, a stretch of railway track, a relay located on a train, means located partly in the trackway for normally energizing said relay but effective under un-

safe traffic conditions to successively de-energize, re-energize and de-energize said relay as the train proceeds through said stretch, apparatus on the train for causing an automatic application of the brakes when said relay is de-energized, manually operable means for preventing such automatic application of the brakes, a signal having a circuit including a front contact of said relay, and means for interrupting said circuit when said manually operable means is in condition to prevent an automatic brake application. 20 25

In testimony whereof I affix my signature.

LLOYD V. LEWIS.
